UNITED STATES PATENT OFFICE.

WILLIAM G. KENDALL, OF NEWARK, NEW JERSEY.

VANITY CASE.

Application filed March 5, 1924. Serial No. 697,091.

To all whom it may concern:

Be it known that I, WILLIAM G. KENDALL, a citizen of the United States, and a resident of Newark, in the county of Essex and State of New Jersey, have invented a new and Improved Vanity Case, of which the following is a full, clear, and exact description.

The present invention relates to vanity cases and it pertains more particularly to an improvement over that shown in my allowed application, Serial No. 634,071, filed April 23, 1923.

It is one of the primary objects of the present invention to provide a cosmetic compact ejecting means which is so constructed as to coact with the cover of the receptacle forming the vanity case, in such a manner as to form a catch for retaining the cover in closed position.

It is a further object of the invention to construct a cosmetic compact ejecting member in such a manner that it is retained within the body of the receptacle forming the vanity case.

It is a further object of the invention to construct the compact ejecting element in such a manner that it may be operated to release the cover and permit of the same being moved to its open position.

With the above and other objects in view, reference is had to the accompanying drawings, in which

Figure 1 is a sectional view of a vanity case constructed in accordance with the present invention;

Fig. 2 is a plan view thereof with the cover shown in the open position;

Fig. 3 is a detail enlarged sectional view taken on the line 3—3 of Fig. 2;

Fig. 4 is a detail front elevational view of the body of the box;

Fig. 5 is a detail view in elevation of a portion of the compact carrier.

Referring more particularly to the drawing, the vanity case comprises a box body 10 having a cover 11. The box body 10 and the cover 11 are pivotally secured together by a suitable hinge 12. Pivotally mounted as at 13, upon the hinge 12, and extending across the bottom of the body 10, there is a relatively narrow strap 14 of suitable material. This strap 14 has an upwardly bent portion 15, which forms the means for pivotally mounting the strap 14 upon the hinge

as heretofore mentioned. At its other end the strap 14 has an upward extension 16.

The reference numeral 17 designates a compact carrier which is adapted to be received upon the strap 14. The upwardly bent portion 16 of the strap 14 is cut as shown at 18 to provide two wings 19, which are adapted to be bent inwardly of the receptacle to engage the angular wall of the compact carrier 17 and to secure the compact carrier 17 in position upon the strap 14. To further aid in securing the compact carrier 17 in position upon the strap 14, the upwardly bent portion 15 of the strap 14 may be provided with a suitable projection, such as 20.

The upwardly bent portion 16 of the strap 14 is further provided with two projections 21 and 22. The projection 21 is preferably elongated in form and projects through an opening 23 formed in the side wall of the box 10. When this projection 21 is engaged in the opening 23, it is obvious that the strap 14 is locked or retained against accidental movement about its pivotal point 13 on the hinge 12. The projection 22 is adapted to engage in a recess 24 formed in the side wall of the cover when the cover is moved to closed position, and by this construction it is apparent that when the projection 22 is in engagement with the recess 24, the cover will be maintained in its closed position.

The device operates in the following manner: The projection 21 carried by the vertical extension 16 of the strap 14 is disengaged from the opening 23 and the strap 14 is swung about its pivotal point 13 to a position outward of the box in which position a suitable cosmetic compact may be positioned on the strap 14 and in retained engagement with the projection 20 and the resilient wings 19.

After this has been done, the strap 14 is swung to position within the box and the projection 21 is engaged in the opening 23 in the side wall of the box to retain the strap 14 in operative position within the box. If, now, the cover be closed, the projection 22 of the vertical extension 16 of the strap 14 will pass into the recess 24 of the cover and serve to maintain the cover in closed position.

When it is desired to open the box, it is only necessary to exert a slight pressure upon the projection 21, when through the resiliency of the vertical extension 16, the

projection 22 will be disengaged from the recess 24 and permit the cover to be swung about the hinge 12 to give access to the interior of the vanity box.

5 From the foregoing it is apparent that the present invention provides a new and improved means for ejecting a cosmetic compact carrier from a vanity case, which means also is constructed in such a manner 10 as to be secured within the box and provides means for securing the cover of the vanity box in closed position.

What is claimed is:

15 In a vanity case, a box body, a cover hing-
edly connected thereto, a strap extending
across the body, said strap being pivotally
connected to the hinge of the box body and
cover, a compact carrier in the body clamped

therein by the end portions of the strap, an upwardly-extending substantially right-angled end portion on said strap at the end opposite to the end connected to the hinge, a plurality of spaced projections carried by said upwardly projecting end portion and extending forwardly thereof, a depression in 25 the cover adapted to receive the uppermost projection to retain the cover in closed position, and an opening provided in the box and adapted to receive the lowermost projection, which lowermost projection provides a 30 thumb-piece operable from the front of the box to release the uppermost projection from its recess to permit of movement of the cover about its pivotal point.

WILLIAM G. KENDALL.
